UNITED STATES PATENT OFFICE

98,613

DESIGN FOR A COMBINED SALES AND DISPLAY COUNTER

Frank L. Pollard, Oakland, Calif.

Application December 26, 1935, Serial No. 60,288

Term of patent 3½ years

To all whom it may concern:

Be it known that I, Frank L. Pollard, a citizen of the United States, residing at Oakland, in the county of Alameda and State of California, have invented a new, original, and ornamental Design for a Combined Sales and Display Counter, of which the following is a specification, reference being had to the accompanying drawing, forming part thereof.

Figure 1 is a front elevational view of the combined sales and display counter.

Figure 2 is an end elevational view thereof.

Figure 3 is a perspective view looking at the rear of the counter.

The base of each unit is finished in a solid color with spaced stripes of a contrasting color to simulate tiling.

The narrow panels, indicated by the criss-crossed lines, adjacent the bottom of each unit, are perforated grilles.

I claim:

The ornamental design for a combined sales and display counter, substantially as shown and described.

FRANK L. POLLARD.
